UNITED STATES PATENT OFFICE.

CHARLES WAINWRIGHT, OF ERIE, PENNSYLVANIA.

CONTROLLING DEVICE FOR FLUID-COMPRESSORS.

1,113,075.

Specification of Letters Patent.

Patented Oct. 6, 1914.

Application filed June 12, 1912. Serial No. 703,245.

To all whom it may concern:

Be it known that I, CHARLES WAINWRIGHT, a citizen of the United States, residing at Erie, in the county of Erie and 5 State of Pennsylvania, have invented new and useful Improvements in Controlling Devices for Fluid-Compressors, of which the following is a specification.

The general object of the invention is to 10 effect automatically the stopping and the unloading of an electrically driven fluid compressor upon the attainment of a predetermined pressure in the receiver of the compressor, and to maintain the compressor 15 unloaded until the receiver pressure has dropped to a predetermined point and the pump mechanism again operating at normal speed. And to this end the invention consists in a controlling device arranged to 20 control the passage of fluid to a fluid actuated switch which controls the motor circuit, and the passage of fluid to fluid actuated mechanism arranged to operate on the intake of the pump mechanism.

25 Other objects will appear and be better understood from that embodiment of the invention of which the following is a specification, reference being had to the accompanying drawings forming a part hereof 30 and in which:—

Figure 1 is a diagrammatic view of the invention. Fig. 2 is an end elevation of the cylinder of the pump mechanism partly in section and disclosing the fluid actuated 35 mechanism for operating on the intake of the cylinder. Fig. 3 is a sectional detail of the means for controlling the passage of fluid to the circuit controlling device and the mechanism for operating on the intake.

40 The compressor *a* may be of the single or multiple stage type, or double acting as shown. It is to be understood that this showing is merely conventional and is given simply to illustrate one application of the 45 invention. The cylinder 5 is suitably connected with the receiver of the compressor. This receiver herein shown is made up of the pipe 6 and container 7. The pump mechanism which includes the piston, not 50 shown, and its connection with the crank shaft 8, is operated by a suitable electric motor, not shown. The motor circuit is controlled by a suitable automatic switch, not shown, and the circuit 9 for controlling 55 the switch, is in turn, controlled by a fluid operated controller or pilot switch 10. The

element 10 may be of any preferred construction and its fluid pressure operated indicator hand 11 is arranged to control the circuit 9 by successively contacting with 60 the contact points 12 and 13.

A pipe connection 14 is established between the switch 10 and a controller 15, which is suitably connected, such as by a pipe 16, to any point in the receiver of the compressor such as the container 7. A pipe 17 conveys the fluid to the mechanism for controlling the intake of the pump mechanism and by preference is connected with a reservoir 18, whose opposite ends are piped as 70 shown at 19—19 to depending cylindrical projections 20—20 at the opposite end portions of the cylinder 5. The intake valves, one of which is shown in Fig. 2 and indicated by 21, are operated through the action of 75 the piston, not shown, but I reserve the right to employ, if so desired, intake valves which are mechanically or otherwise actuated. In each of the cylindrical extensions 20, is arranged a plunger. One of such 80 plungers is shown in Fig. 2 and indicated by 22, and referring to the said Fig. 2 it will be observed that the plunger projects into the valve cage 23 and its upper end is normally spaced from the stem 24 of the 85 valve 21. The plunger is so arranged with respect to the pipe 19, that the fluid which passes through the said pipe and into the cylindrical extension 20, will lift the plunger 22 into contact with the valve stem 24 90 and thereby unseat the valve 21.

A check valve 25 is connected in the pipe 17 and prevents the return of fluid into the pipe connection 14, and a vent or choke 26 is arranged so as to form the exhaust of the 95 reservoir 18.

In use the adjustment of the controller 15 is effected by turning the plug 27 which regulates the tension of the spring 28. With the spring adjusted so as to yield only under 100 a certain pressure in the receiver of the compressor, and the needle valve 29 carried by the plunger 30 closing the passage 31 to the pipe connection 14, the effect obtained upon the attainment of a pressure in the receiver 105 7 sufficient to overcome the tension of the spring 28 will be as follows:—First, the fluid will lift the valve 29 and its plunger and pass into the pipe connection 14 and into the switch 10. Here the indicator 11 110 will be moved from the contact 12 to the contact 13 and thereby effect the breaking or

opening, through the automatic switch, not shown, of the motor circuit and the consequent stopping of the motor. From the pipe connection 14 the fluid will pass 5 through the check valve 25 and into the reservoir 18 through the pipe 17. From the reservoir the fluid will pass through the pipes 19—19 and operate to lift the intake valves through the plungers in the extensions 20—20. Thus it will be seen that substantially synchronously with the stopping of the motor, the unloading of the cylinder 5 will be had, and these effects will continue until the pressure in the receiver is 10 so reduced as to admit of the spring 28 closing the valve 29. When this is brought about, the air entrapped in the pipe connection 14 will escape through the vent 32 and permit the return of the indicator 11 to its 15 normal position as shown in Fig. 1 whereupon the motor circuit will be closed and the motor caused to operate. At this time, however, the air entrapped in the pipe 17 will be prevented by the check valve 25, from 20 returning or backing into the pipe 14, and inasmuch as the volume of the reservoir 18 is relatively large as compared with the volume of the pipe connection 14, it will be manifest that the pressure in such reservoir 25 will keep the plungers 22 raised and the inlet valves 21 open after the closing of the motor circuit by the switch 10 so that the cylinder will remain unloaded when the motor and the pump mechanism begin to operate and 30 will remain so unloaded until the motor and the said pump mechanism are operating at normal speed. When sufficient fluid is exhausted through the choke 26 to admit of the descent of the pistons 22, the pump mechanism will become active and compress 35 into the receiver as before.

From the foregoing it will be observed that the arrangement of parts is such as to render the construction extremely simple and efficient and usable with any type of electrically driven compressor equipped with 45 any automatic self-starting and stopping device, and regardless of the kind of current used for the motor of such compressor.

What I claim as new is:—

In an electrically operated fluid compressor, embodying a suitable compression chamber, receiving tank, and electric motor, the combination of a manually adjustable spring controlled valve communicating with the receiver and adapted for being opened by fluid pressure from said receiver, a pipe leading from said valve, a double branch pipe connected to the said pipe, one branch of which communicates with a fluid controlled switch whereby the motor circuit is opened or closed, the other branch leading through a suitable check valve and a vent, a reservoir disposed adjacent to the compression chamber and with which the last mentioned branch connects at a point between its ends, 65 said reservoir having a pipe leading from each end and communicating with a fluid controlled valve provided in the ends of the compression chamber, said valves being adapted for being opened by the pressure of 70 the fluid in the reservoir whereby the compression chamber is relieved of excessive pressure, simultaneously with the opening of the switch.

In testimony whereof I affix my signature in presence of two witnesses.

CHARLES WAINWRIGHT.
